INFANT SWING SEAT

Fred E. Golding, South Pasadena, Calif., assignor to Aeon
Industries, Inc., doing business as Pride Products Com-
pany, Glendale, Calif., a corporation of California

Filed June 7, 1967, Ser. No. 7,388

Term of patent 14 years

U.S. Cl. D15—1
Int. Cl. D21—04; D6—01

FIG. 1

FIG. 2.

FIG. 3.

FIG. 4.

FIG. 1 is a perspective view of an infant swing seat showing my new design;

FIG. 2 is a top plan view of the infant seat;

FIG. 3 is a side elevational view of the infant seat; and

FIG. 4 is a rear elevational view of the infant seat.

I claim:

The ornamental design for an infant swing seat, substantially as shown.
